Application January 31, 1949, Serial No. 73,856

Claims priority, application Spain
November 10, 1948

2 Claims. (Cl. 33—172)

1

In internal combustion engines, especially those intended for automobile vehicles, Bosch pumps are frequently employed for the supply of fuel to the cylinders, or pumps of other similar types which comprise a centrifugal governor mounted on the pump itself and actuated by the engine in order to determine the variations in the supply of fuel corresponding to variations in the load on the engine.

This invention relates to indicating apparatus which is fitted to the pump itself, and indicates directly by means of a needle or pointer which moves over a dial, the supply of fuel, and hence the power the engine is developing.

This apparatus comprises a plunger or sliding member which is actuated directly by the moving part of the centrifugal governor, and which rocks a lever, which in its turn actuates a toothed wheel or sector, which meshes with a toothed pinion on the spindle of the indicator needle or pointer. A suitably placed spring constantly presses the lever against an abutment on the sliding plunger, and hence presses this plunger against the moving part of the governor, so that the position of the needle on the dial is always related to the position of the moving part of the governor, which, by means of a lever, controls that member of the pump which regulates the quantity of fuel supplied to the engine.

A modification of the apparatus comprises the coupling of the spindle of the pinion by means of a flexible shaft or other mechanical connection, with a needle situated on a dial remote from the apparatus itself, and situated for example on the control dash-board, in the case of an engine installed on a motor vehicle.

Apparatus according to the invention is illustrated in the accompanying drawings, in which:

Figure 1 shows diagrammatically in sectional elevation the application of the apparatus to a pump of the Bosch type provided with a governor.

Figure 2 is an outside view of the apparatus from the front;

Figure 3 shows a section on the line III—III in Figure 2; and

Figure 4 shows a section on the line IV—IV in Figure 3.

The fuel pump of the engine comprises a centrifugal governor comprising two weights 1 mounted on a shaft 2. The weights or masses 1, on being displaced by the action of centrifugal force resisted by an opposing spring 3, displace along the shaft 2 a sleeve or moving part 4, 55

which, by means of a lever 5, actuates a member 6 controlling the pump, in such a direction as to increase the quantity of fuel injected into the engine when the speed of this latter is decreased through an increase in load, and to diminish the quantity of fuel when the load decreases and the speed of the engine increases.

The apparatus of this invention is fixed to the external casing or cover 7 of the pump as shown diagrammatically in Figure 1, and comprises a main shaft or spindle 8 (Figures 3 and 4) which rotates in bearings 9 mounted in the casing of the apparatus, and carries at its free front end a needle 10, which moves over a dial 11.

15 At the lower part, the apparatus comprises a slide or sliding plunger 12, which, on the apparatus being mounted on the pump as indicated in Figure 1, bears with its free end against the moving sleeve 4 of the governor, so that when 20 this moving sleeve of the governor is displaced to the left of Figure 1 it pushes the plunger 12 before it, and when it is displaced to the right it permits the plunger 12 to move back with it through the action of an opposing spring 15.

25 On the shaft 8 of the indicator needle or pointer is mounted loosely, through the medium of a bearing 16, a lever 17, the lower end 18 of which bears against a projection 19 on the plunger 12, while its upper arm is actuated by the spring 15, which always tends to press the lower arm of the lever against the projecting part of the plunger 12 and consequently to press the plunger 12 against the moving part 4 of the governor.

30 35 The lever 17 terminates at its upper end in a fork which fits on a button or pin 20 fixed to a toothed wheel 21, so that when this lever 17 oscillates it causes the toothed wheel to rotate, and this latter amplifies the movement and transmits it to a pinion 22 fixed to the shaft 8 which carries the indicator needle or pointer 10. Consequently the position of this needle or pointer 10 on the dial 11 indicates at every moment the position of the regulating member 6 of the injection,

40 45 50 and hence the quantity of fuel that is being injected into the engine. As this quantity of fuel corresponds to the power which is being exacted from the engine the needle or pointer 10 constantly indicates how much power the engine is developing.

In order to facilitate in each case the regulation of the apparatus with relation to the engine to which it is applied, the plunger 12 is provided with a sliding stop 13, which projects 55 at the end of the plunger, and the position of

which is adjusted by means of a screw 14, so that by turning this screw the length of the plunger, and hence the position of the lever 17 with relation to the moving part of the governor, are conveniently regulated. In addition, it is also possible to regulate the coupling of the lever 17 with the toothed wheel 21, for which purpose in this wheel 21 there are various holes 23, in any one of which it is possible to fix the pin 20 that fits into the fork of the lever 17.

When this apparatus is applied to an internal combustion engine mounted on an automobile vehicle, it is not in general convenient to read the indications of the indicator needle or pointer in the apparatus itself, and in such a case it is possible to connect the device with another dial and indicator needle on the dash-board of the vehicle or at any other suitable point, and to couple the needle of this dial with the spindle of the indicator needle of the apparatus by means of a flexible cable or other suitable transmission gear.

Thus, for example, it is possible to arrange at the end of the spindle 8 of the indicator needle a bevel wheel 25, which meshes with another bevel wheel 26 fixed to a shaft 27, which has coupled to it a flexible cable 28, which transmits the movements to the needle or pointer of a dial of any suitable type arranged on the dash-board of the vehicle.

I claim:

1. Apparatus for facilitating controlling the functioning of an internal combustion engine and the like comprising a slidable plunger, a lever actuatable by said plunger, a toothed wheel connected to said lever and movable thereby, an indicator needle, a shaft mounting said needle, a bearing loosely mounting said lever on said

needle shaft, a pinion on said shaft meshing with said toothed wheel, said indicator needle being positioned in direct correspondence with the position of said slideable plunger at any given moment, a projection on said plunger, adjustable means in said plunger, said projection being adjustable in position by said adjustable means, the lower end of said lever being in contact with said plunger, the position of the upper end of said lever being determined by the adjustment of said adjustable means in said plunger for adjusting the position of said needle.

2. Apparatus as claimed in claim 1, and wherein in said lever actuated by said plunger terminates in a fork, said toothed wheel having a plurality of holes therein, a pin fixed in one said hole in said toothed wheel, said pin being slideable in said fork, said pin being adjustable to different positions on said toothed wheel by fixing in different ones of said holes for regulating the position of coupling of said lever and said toothed wheel.

ALBERTO LAGARDÈRE.
